UNITED STATES PATENT OFFICE

RUDOLF VON FROMMER, OF BUDAPEST, HUNGARY

DESIGN FOR A RIB FOR SPORTING GUN

Application filed July 8, 1927, Serial No. 22,691, and in Hungary March 19, 1927. Term of patent 14 years.

To all whom it may concern:

Be it known that I, RUDOLF VON FROMMER, a subject of the Kingdom of Hungary, residing at 158 Soroksári ut, Budapest, Hungary, have invented a new, original, and ornamental Design for rib for sporting gun, of which the following is a specification, reference being made to the accompanying drawing, forming part thereof.

Fig. 1 is a top plan view of a gun showing my design for the rib thereof, the rib being

shown in full lines and the gun in dotted lines;

Fig. 2 is an enlarged detail plan view of the rib removed from the gun; and

Figs. 3 and 4 are edge and end elevations of the rib.

I claim:

The ornamental design for a rib for sporting gun as shown.

RUDOLF VON FROMMER.
